CLAIM

The ornamental design for a hand held power pruner, as shown.

DESCRIPTION

FIG. 1 is a perspective view of a hand held power pruner showing our new design;

FIG. 2 is a rear perspective view thereof;

FIG. 3 is a front perspective view thereof;

FIG. 4 is a right side elevational view thereof;

FIG. 5 is a left side elevational view thereof;

FIG. 6 is a front, slightly in perspective view thereof;

FIG. 7 is a rear, slightly in perspective view thereof;

FIG. 8 is a top plan view thereof; and,

FIG. 9 is a bottom plan view thereof.

The broken lines showing a portion of a cord in FIG. 1 are for illustrated purposes only and form no part of the claimed design.

FIG. 4

FIG. 5

FIG. 6

FIG. 7

FIG. 8

FIG. 9
